UNITED STATES PATENT OFFICE

2,601,819

BUILDING CONSTRUCTION

Frank A. Redford, Long Beach, Calif.

Application November 26, 1947, Serial No. 788,269

4 Claims. (Cl. 98—29)

1

This invention apparatus to novel and useful improvements in building constructions.

An object of this invention is to supply a strong, durable, attractive, sanitary, stationary wigwam-type construction including the feature of providing an improved window construction for use particularly with wigwam-type buildings, wherein an outer window is placed in juxtaposition to an inner window, the outer window having flashing thereon and a baffle positioned beneath both the outer and inner window, inclined toward the outer window for directing liquid to the lower portion of the said outer window, and more specifically, a port therein for drainage.

Another feature of the invention includes an improved type of filler for use in the upper portion of the outer sloping form wherein a cementitious product is supplied having vent pipes rigidly secured therein for directing gases from various appurtenances such as the water closet, heater and the like.

Another feature of this invention is to provide a stationary structure anchored to a slab, the ceiling extending from suitable points on the outer frame serving the purpose of a support for the said outer frame.

Ancillary objects and features of novelty will become apparent to those skilled in the art, in following the description of the preferred embodiment illustrated in the accompanying drawings, wherein:

Figure 1 is a front view of the preferred form of the invention;

Figure 2 is a sectional view taken transversely of Figure 1;

Figure 3 is a sectional view taken substantially on the line 3—3 of Figure 2 and in the direction of the arrows;

Figure 4 is a section of the framing forming a portion of the outer frame;

Figure 5 is a view of a section of the door framing utilized in the outer frame;

Figure 6 is an elevational fragmentary view illustrating the door framing in the inner frame;

Figure 7 is a plan view of the filler or closure and showing a portion of the framing connected therewith;

Figure 8 is a sectional view of the filler or closure at the top of the outer frame;

Figure 9 is a detailed view of the door in the outer frame with portions of the cover removed to illustrate details of construction;

Figure 10 is a sectional view taken substantially on the line 10—10 of Figure 9 and in the direction of the arrows;

2

Figure 11 is a window detail illustrating the preferred construction;

Figure 12 is a side view of the outer frame and inner frame adjacent the windows;

5 Figure 13 is a front view of the detail of construction illustrated in Figure 12;

Figure 14 is a fragmentary detail of construction illustrating the slab construction with the outer frame secured thereto;

10 Figure 15 is a sectional view taken substantially on the line 15—15 of Figure 14 and in the direction of the arrows;

Figure 16 is a perspective view of the filler or closure utilized at the apex of the outer frame, and;

15 Figure 17 is a fragmentary sectional view illustrating the base detail preferred for use in association with the inner frame adjacent the slab or floor.

20 A building construction in accordance with this invention includes a slab 10 of polygonal configuration with a footing 12 therebeneath and of course, sunk in the ground. A walk 14 may be supplied as a continuation of the slab.

25 A main frame generally indicated at 16 is of polygonal cross-section and pyramidal contour. By this pyramidal contour, the walls are of necessity sloping as is seen in Figure 1.

The makeup of the said outer frame 16 is preferably in accordance with the detail illustrated in Figure 4. A plurality of studs 18 are provided with various truss members 20 associated therewith for strengthening purposes. Any number of these sections 18 are juxtaposed with 30 the corners properly mitered to form the said outer frame 16.

The lower portions of each of the said sections 18 are placed upon a base strip 22 and suitable anchor bolts 24 extend therethrough, which of course, terminate in the slab 10. A baffle or mudboard 26 may be supplied for weatherproofing purposes. This mudboard or baffle 26 is preferably metallic and simply anchored by means of conventional nails.

45 When the outer frame 16 is properly positioned, a cover of any suitable material such as plaster or the like may be supplied thereover. Of course, any cover may be used in this connection without departing from the spirit of the invention.

Referring now to Figure 5, it will be seen that a modified form of the section 18 is illustrated and is generally indicated at 28. This section 28 is to be positioned at a selected point in the said outer frame 16 adjacent the walk 14. Certain 50 of the truss members are removed in order to

provide an adequate doorway. A sill 30 is supplied at the lower portion of the said section 28. A plurality of graduated size templates 32 having one arcuate surface is secured to the outer frame 16 adjacent the said frame section 28. Suitable metal screen 34 is supplied over these templates and then, the waterproof cover means is positioned thereon. This forms a rolled effect adjacent the doorway of the outer frame, simulating the turn-back door or entrance to a conventional wigwam.

Noting Figure 8 primarily, it will be seen that the top end of the outer frame is connected with a closure or filler generally indicated at 36. This filler consists of an inner sleeve 38 having a cementitious product therein such as the concrete 40, and a skirt 42 attached to the said sleeve. This skirt 42 may be conventionally connected such as by soldering, welding or the like. It is noted that the said skirt is flared and partially overlaps the sleeve 38 and overlaps the wigwam framing to serve as flashing. Between the said skirt and the sleeve, the ends of the said frames 18 are positioned and secured by means of suitable conventional bolts 44 or the like.

Extending through the cementitious product 40 is a plurality of conduits or vents 46 which are utilized for the purpose of exhausting undesired gases which accumulate within the wigwam.

An interior or inner frame, generally indicated at 50, is supplied within the said outer frame and may be seen best in Figures 2 and 3. This inner frame is provided of a plurality of sections 52 which are vertical. These sections 52 and in fact the inner frame 50 is seated on the said slab 10 and anchored by means of suitable anchor bolts 54. Of course, where it is desired, a baseboard 56 may be supplied which is connected with not only the slab 10 but also a plywood or the like cover 58 for interior decorative and partitioning purposes.

Noting Figure 2, it will be seen that the area between the inner wall and the outer wall or inner frame and outer frame is a furring space or area for insulating purposes and for receiving various and sundry appurtenances contiguous to domiciles. A partition 60 and a second cooperating partition 62 is supplied for defining several rooms within the inner frame construction. The said partition 62 forms one wall of a shower room 64 which may have tiles 66 therein. The said partition 60 defines a room containing a water closet, wash basin and the like. Of course, a dividing partition 68 may be supplied in association with these two rooms and a sliding door 70 is associated with the cooperating partitions 62 and 60. This sliding door is of material importance in the present invention since in constructions of this nature space is at a premium and a sliding door utilizes substantially no additional space.

A ceiling is supplied over the main room 72 and consists of a plurality of rafters 74 having a portion of the said cover 58 fixed to the lower surfaces thereof and a platform 76 fixed to the upper surfaces thereof. A heater 78 may be positioned on the said platform 76 if so desired. Of course, with the heater in this position, the vent pipes 46 are used to conduct the gases emitted therefrom.

A second portion of the ceiling indicated at 79 is supplied over the rooms defined by the said partitions 62, 60 and 68. It will be noted, however, that both of the said ceiling means are secured

to the outer wall or outer frame member 16 thereby rendering additional support for the sectional elements 18 cooperating to make up the outer frame.

5 A doorway is provided directly behind the sectional element 28 and the preferable door frame may be seen in Figure 6 wherein a pair of uprights 80 and 82 respectively are joined by a cross member 84 thereby forming the doorway in the inner frame member 50. A conventional door or closure 86 is supplied in the door jamb construction illustrated in Figure 6, and of course, utilizes conventional hinges.

Referring now to Figures 11 through 13, reference is made primarily to the window construction and the drainage means associated therewith. In the inner frame 50 there is supplied a substantially conventional vertically disposed window jamb indicated at 90 with a window 92 therein. Of course, glass is utilized in association with the window. Juxtaposed relative to the window 92 provided in the inner frame 50, there is supplied an outer window 94 which is secured to the outer frame 16 and slopes therewith. This outer window is composed of a frame and has flashing or a small gutter 96 at the top portion thereof to direct rain water which flows down the walls away from the window. Support members 98 extend from beneath the inner window 92 to the lowermost portion of the outer window 94, being downwardly inclined. A baffle 100 is seated thereon whereby rain water entering the open outer window is directed to the lowest part of the outer window, where it 20 drains from between the windows. In the furred area adjacent the doors there is supplied a closet 102 with a conventional closure or door 104 associated therewith. On the opposite side of the doors there is a second identical closet 106 which has a unit 108 positioned therein for conditioning air. A suitable vent (see Figure 1) 110 is supplied in the outer frame and through the cover for the outer frame, whereby fresh air may be selectively received and spent air exhausted. This of course, renders the wigwam air-conditioned.

There has been described and illustrated but a preferred form of the present invention. However, it is apparent that variations may be made such as subjecting the structure to different uses and rearranging certain elements without departing from the spirit of the invention. Therefore, limitation is sought only in accordance with the scope of the following claims.

55 Having described the invention, what is claimed as new is:

1. In a building construction of the wigwam type, a slab, an outer frame tapering from its bottom to its top seated on said slab, a filler positioned at the top of the outer frame, means for anchoring the filler to the top of the outer frame including flashing and means containing said filler fixed to said flashing, vent conduits extending through said filler, and a covering on said outer frame.

60 2. In a building construction of the wigwam type, an outer frame tapering from its bottom to its top and having an opening in the top, a covering disposed on said outer frame and terminating at said open top, a sleeve disposed in said open top and having a plurality of vent pipes therein forming an ornamentation for the top of the frame, and a tapered skirt 65 secured to the upper end of said sleeve and over-

lapping a part of said outer frame adjacent to said opening to serve as flashing.

3. In a building construction of the wigwam type, an outer frame tapering from its bottom to its top and having an opening in the top, a covering disposed on said outer frame and terminating at said open top, a sleeve disposed in said open top and having a plurality of vent pipes therein forming an ornamentation for the top of the frame, means consisting of a cementitious product disposed in said sleeve and having said conduits embedded partially therein to hold said conduits within said sleeve, the upper ends of said conduits being disposed exteriorly of said frame, and said sleeve having flashing secured thereto.

4. In a building construction of the wigwam type, an outer frame tapering from its bottom to its top, an inner frame disposed in said outer frame, and means forming an ornament at the top of said outer frame, including a sleeve disposed in the open top of said outer frame with a number of vent conduits therein, a flange disposed along the periphery of said sleeve and engaged over the upper end of the outer frame

to hold said sleeve fixed in the open end of said outer frame, and a cementitious product in said sleeve holding said conduits fixed therein.

FRANK A. REDFORD.
